CLAIM

The ornamental design for a braced base for a pole as shown and described.

DESCRIPTION

FIG. 1 is a front, top, perspective view of a braced base for a pole showing my new design;

FIG. 2 is a right side elevational view, the left side elevational view being a mirror image thereof;

FIG. 3 is a top plan view; and,

FIG. 4 is a bottom plan view.

The braced base for a pole is shown with a symbolic length in FIGS. 1 and 2. The appearance of any portion of the article between the break lines forms no part of the claimed design.
